UNITED STATES PATENT OFFICE.

ALBERT M. ROSS, OF GRAND ISLAND, NEBRASKA.

CONTAINER-CUTTING MACHINE.

Application filed February 11, 1927. Serial No. 167,473.

The invention relates to a container forming and cutting machine, and has for its object to provide a device of this character particularly adapted for placing incisions 5 in opposite sides of a strip of paper and for severing the strip when desired whereby strips are formed which may be easily and quickly bent to cylindrical form, and interengaged by the opposite slits for forming a 10 plant shield or container. The device is particularly adapted for forming plant shields.

A further object is to provide a machine wherein a plurality of strips may be fed 15 through the same simultaneously and simultaneously cut.

A further object is to provide superimposed feed rolls through which the strips pass, and by the rotation of which feed rolls 20 the strip may be fed through the machine.

A further object is to provide pivoted members on the knives, which members limit the downward movement of the knives and the length of the incisions in opposite sides 25 of the strip and when pivoted upwardly and held allow the knives to sever the strip into sections.

With the above and other objects in view the invention resides in the combination and 30 arrangement of parts as hereinafter set forth, shown in the drawing, described and claimed, it being understood that changes in the precise embodiment of the invention may be made within the scope of what is 35 claimed without departing from the spirit of the invention.

In the drawing:—

Figure 1 is an end elevation of the machine.

Figure 2 is a side elevation of the machine.

Figure 3 is a perspective view of one of the plant shields formed from one of the strips.

Figure 4 is a top plan view of the machine.

Figure 5 is a plan view of one of the strip sections before bending to cylindrical form.

Referring to the drawing, the numeral 1 50 designates the frame of the machine which is rectangularly shaped as shown, and provided with supporting legs 2 which may be anchored to the floor in any suitable manner. Rotatably mounted within the frame 1 is a feed roller 3 with which a superimposed weight roller 4 cooperates, and between

which rollers the plant shield strips 5 extend and are fed when the operator rotates the roller 3 by means of a crank 5. The plant shield strip 5 extends rearwardly over the 60 guide plate 7 and to paper rolls 8 from which they are fed, and which rolls are supported preferably on transversely disposed rods 9. It will be noted that four rolls 8 65 are shown of strip paper, however it is to be understood that any number desired may be used, and four are shown for purposes of illustration only. By providing a plurality of rolls 8, it is possible by the mechanism 70 hereinafter set forth to sever and cut a plurality of strips 5^a as shown in Figure 5 for forming the plant shield 10 shown in Figure 3.

Pivottally connected at 11 to one side of the strips is a knife 12, which knife is 75 adapted to be grasped by the operator and moved downwardly for cutting a slot 13 in the adjacent side of the strip at any desired point, and pivottally connected at 14 to the opposite side of the machine is a knife 15 80 adapted to be moved downwardly for cutting a slot 16 in the opposite side of the strip of material. The slots 13 and 16 extend substantially to the longitudinal 85 center of the strip whereby when the strip 5^a is formed and bent to cylindrical form, said slots may be placed in interengagement 90 for forming the cylindrical plant shield 10 adapted to be placed around plants for protecting the same.

Pivottally connected to the knives 12 and 15, are arms 17, which arms, when the knives are moved downwardly engage adjacent parts of the machine and limit the movement of the knives whereby they will not 95 sever the strip entirely across, however after the forming of the slots 13 and 16 said strips may be severed entirely across for forming the members 5^a by swinging the members 17 100 upwardly with the finger where they will not engage any part of the machine and limit the movement of the knives, consequently the strips may be transversely severed in the desired lengths. Extending beyond one end of the machine is a tray 18 105 into which the strips may drop or be deposited as they are severed.

From the above it will be seen that a strip cutting and severing device is provided 110 which is particularly adapted for cutting strips of material to be used as plant shields, but which may be used for cutting strips to

form bodies of containers. It will also be seen that a plurality of elongated strips may be formed with slots extending inwardly from opposite sides thereof simultaneously, thereby allowing plant shields to be cheaply manufactured and sold and to be shipped in flat condition and bent to form as used.

5 The invention having been set forth what is claimed as new and useful is:

19 A container body cutting machine comprising a frame, superimposed feed rollers carried by said frame, means for supporting rolls of strip material on the frame, spaced cutter bars, superimposed feed rollers be-

tween said cutter bars, means for rotating 15 said feed rollers for feeding strips longitudinally, and knives pivoted at opposite sides of the strip and cooperating with the cutter bars, said knives having limiting means thereon whereby in cutting slits in 20 opposite sides of the strips they will be limited in their movement such limiting means being movable for allowing unlimited movement of the knives whereby said strips may be entirely severed.

25 In testimony whereof I hereunto affix my signature.

ALBERT M. ROSS.
